ANCHORING DEVICES FOR WELL TOOLS
Jack W. Tamplen, Celina, Tex., assignor to Otis Engineering Corporation, Dallas, Tex., a corporation of Delaware
Filed Oct. 14, 1965, Ser. No. 495,910
14 Claims. (Cl. 166—137)

ABSTRACT OF THE DISCLOSURE

An anchoring device having locking dog expander means having dual wedging members for positively locking the locking dogs in expanded position and providing for ready release when desired. Sealing means is initially mechanically expanded to sealing engagement and is then pressure actuated.

This invention relates to well tools and more particularly relates to an anchoring device for locking a body against movement within a flow conductor.

An object of the invention is to provide a new and improved anchoring device.

Another object of this invention is to provide a new and improved anchoring and sealing device.

It is a particularly important object of the invention to provide an anchoring device having "pressure energized" slips which are both expandable into tighter engagement with and are releasable from a surrounding surface by forces exerted in the same direction.

It is another object of the invention to provide an anchoring device having a locking slip assembly including members having adjacent fragmentary conical surfaces which are in full engagement or fully seated against each other when the slips are fully expanded and which are only partially seated with each other when the slips are contracted to their normal inward positions.

It is another object of the invention to provide an anchoring device including interconnected slips and slip shoes which move longitudinally as a unit during the initial phases of locking while the slips move laterally or radially independent of the slip shoes during the latter phases of locking.

It is another object of the invention to provide an anchoring device having slip operators which when moved longitudinally toward the slips initially move the slips and slip shoes as a unit, then laterally expand the slips independently of the slip shoes, and when moved away from the slips are withdrawn from within the slips to permit inward retraction of the slips.

It is another object of the invention to provide an anchoring device including expandable slips held around a frusto-conical expanding surface by first lateral springs connected between the slips positioned on opposite sides of the expanding surface and urged toward the base of the surface by a second longitudinally compressible and expandable spring.

It is a further object of the invention to provide an anchoring device having slips which are forced into tighter engagement with a surrounding surface by upward force on the mandrels of the device and are releasable by an upward force applied to the fishing neck of the device.

It is another object of the invention to provide an anchoring and sealing device having an annular sealing element which after an initial seal is established with a surrounding surface is further expanded by a fluid pressure applied either above or below the element.

It is another object of the invention to provide an anchoring and sealing device for sealing above a well device in a tubing section and holding such well device against upward movement within the tubing.

2

It is still a further object of the invention to provide an anchoring and sealing device useful as a member of a pack-off assembly for isolating leaks in a section of tubing to reestablish flow through the tubing.

5 Additional objects and advantages of the invention will be readily apparent from the reading of the following description of a device constructed in accordance with the invention, and reference to the accompanying drawings thereof, wherein:

FIGURES 1 and 1A taken together constitute a longitudinal view partially in section and partially in elevation of an anchoring and sealing device constructed in accordance with the invention;

15 FIGURE 2 is a slightly reduced exploded perspective view of a slip, a slip operator, and a slip expander used in the device of FIGURES 1 and 1A;

FIGURE 2A is a perspective view of a slip retainer spring used in the anchoring and sealing device;

20 FIGURE 3 is a view in section along the line 3—3 of FIGURE 1;

FIGURE 4 is a reduced fragmentary side view in elevation illustrating a slip, a slip operator, and a slip shoe as viewed through a side window in the locking sleeve of the anchoring and sealing device;

25 FIGURE 5 is a reduced fragmentary longitudinal view partially in section and partially in elevation illustrating a running tool engaged on the upper mandrel and fishing neck of the anchoring and sealing device;

FIGURE 6 is a reduced fragmentary view in section 30 illustrating the anchoring and sealing device at an intermediate state in its operation showing the sealing element expanded and a slip expanded to a position of initial contact with a surrounding surface; and

FIGURE 7 is a reduced fragmentary view in section 35 similar to FIGURE 6 showing the fully expanded position of one of the slips.

Referring to the drawings, the anchoring and sealing device 20 embodying the invention includes a mandrel 20a comprising an upper mandrel section 21, a middle 40 mandrel section 22 threaded on a lower end section 23 of the upper mandrel section, and a bottom mandrel section 24 threaded on a lower end section 25 of the section 22. A slip assembly 28 is supported on the mandrel 20a for lateral expansion and contraction to releasably engage the anchoring and sealing device with a surrounding surface such as an inner wall 29 of a tubing section 30. An annular seal assembly 31 is supported on the middle mandrel section for radial expansion to seal with the tubing wall around the device. A longitudinal bore 32 extends through the mandrel to allow fluid flow throughout the entire length of the device. A tubular sleeve shaped fishing neck 33 fits in sliding relationship around the upper mandrel section for supporting the device during its installation and removal and for expanding and releasing the slip assembly. The threaded lower end section 34 of the bottom section serves to connect the device with a well tool or object which the device serves to seal above and hold against upward movement within the tubing 30.

The slip assembly 28 includes two laterally expandable and contractable slips 35 which are yieldably interconnected by two hairpin shaped transversely acting springs 40. Each of the slips is supported on a slip shoe 41 and a slip operator 42. The slips and their respective slip shoes and operators are positioned in 180-degree circumferentially spaced relationship on the cylindrical outer surface of the upper mandrel section 21 and a frusto-conical expander surface 43 of the upper end section 44 of the middle mandrel section. Each of the slips is laterally or radially movable through a side window 45 formed in an operator sleeve 50 which is threaded on a lower reduced end section 51 of the fishing neck 33 and extends

downwardly over portions of the upper and middle mandrel sections.

Each slip shoe 41 has an upper inner fragmentary cylindrical surface 52 corresponding to the outer surface of the upper mandrel section 21 and a lower inner fragmentary conical surface 53 corresponding to the outer frusto-conical expander surface 43 on the middle mandrel section. As shown in FIGURE 2, two fragmentary flange sections 54 and 55 are formed on the lower end of the slip shoe in spaced-apart relationship to provide a slot 60 to receive a portion of a slip to interlock the slip shoe with its slip as will be explained in more detail herein-after. The outer surface 61 of each slip shoe is a fragmentary conical surface which lies parallel to the inner fragmentary conical surface 53 of the slip shoe.

The upper portion 62 of the inner surface of each operator 42 is a fragmentary cylindrical surface corresponding with the outer surface of the upper mandrel 21 while the lower inner surface portion 63 of the operator is a fragmentary conical surface corresponding with the surface 61 on the slip shoe. An upper end flange 64 is formed on each operator providing an upper end surface 65 which is engageable by the upper surface 70 of the operator sleeve 50 defining the upper end of the window 45 in which the operator is positioned. The opposite ends of the flange 64 extend outwardly from the main body of the operator to form the lateral ears or lugs 71 and 72 which are received in the lateral end recess portions 73 and 74, respectively, of the window 45 to limit longitudinal and rotational movement of the slip operators relative to the operator sleeve. The outer surface 75 of each slip operator is a fragmentary conical surface corresponding to the fragmentary conical inner surface 80 of each of the slips 35. The outer portion of each of the slips is provided with a plurality of horizontal teeth 81 which are formed in a fragmentary cylindrical surface so that when the slips are expanded the edge of each tooth will fully engage the inside cylindrical surface 29 of the tubing 30. A downwardly extending lug or tongue 82 formed on the lower end of each of the slips is received in the slot 60 of the supporting slip shoe. An inwardly extending lip or boss 83 on the lug 82 hooks over the lower end of the slip shoe within the slot 60 to hold the slip against upward movement relative to the slip shoe. Similarly, each slip is held against downward movement on its shoe by the flange sections 54 and 55 which engage the lower end of the slip on each side of the lug 82. The vertical side edges of each of the slips has a horizontal blind hole 84 which receives a hooked or bent end 85 on one of the springs 40 for interconnecting the spring and the slip.

Each of the hairpin springs 40 comprises an upwardly extending V or a bight section 90 having an apex 91, horizontal sections 92, and the end sections 85 which are bent perpendicular to the sections 92 into a horizontal plane which extends perpendicular to a plane passing through the V-section 90. Each of the two springs is positioned along corresponding side edges of the oppositely located slips 35 with an end section 85 received in each hole 84 of the slips and the V-portion 90 of each spring extending substantially longitudinally along the outer surface of the mandrel section 21 spanning the space between the slips so that the combined action of the two springs 40 holds each slip and its respective slip operator and shoe on the outer surface of the upper mandrel section and the conical expander surface of the middle mandrel section. The operator sleeve 50 is concentrically positioned around and spaced from the upper mandrel a sufficient distance to provide a fragmentary annular space 93 within the sleeve around the mandrel above the expander surface 43 on the sides of the slip. Each space 93 accommodates the portions 90, 91, and 92 of one of the springs 40. A portion of each section 92 of each spring 40 adjacent to and connecting with an end section 85 of the spring is positioned within an enlarged section or side recess 94

of its window 45 allowing both longitudinal and lateral movement of the springs 40 during expansion and contraction of the slips. The inward force applied to the slips by the springs 40 biases each slip and its operator and shoe inwardly and upwardly along the sloping expander surface 43.

The frusto-conical surface 43 along with the fragmentary conical surfaces on the slip shoes, slip operators, and slips are all so shaped that when the slips are fully expanded as in FIGURE 7, the adjacent contacting conical surfaces are fully engaged with each other. For example, the inner conical surface 53 of each slip shoe engages the conical expander surface 43 and the inner conical surface 63 of each slip operator engages the outer conical surface 61 of the adjacent slip shoe as do adjacent surfaces of the slips and operators. Obviously, with these conical surfaces so contoured that they are in full engagement with each other when the slip assembly is fully expanded the surfaces are out of register or do not fully contact each other when the slips are in the retracted position as illustrated in FIGURE 1. This lack of registry between the conical surfaces on the different portions of the slip assembly results from the fact that in the retracted position surfaces having unequal radii are aligned while in the fully expanded position the conical surfaces are so aligned that each set of contacting adjacent conical surfaces have equal radii and thus will fully seat with or engage each other. Such relationship of adjacent surfaces of the various slip assembly components is desirable when the slips are fully expanded so that there is an essentially solid connection provided between the mandrels of the anchoring and sealing device and the inside surface of the tubing to provide better support for holding the tool against upward movement.

The bore 95 through the fishing neck 33 is enlarged along a lower end section 96 forming a downwardly opening annular recess 100 around the upper mandrel section 21 to receive a spring 101 which is closed and ground at its lower end 102. The apex 91 of each spring 40 extends into the annulus 100 to engage the lower end 102 of the spring 101 and compress the spring so that the force of the spring bears against the upper end of each of the springs 40 to bias them and the slips in a downward direction relative to the mandrels and the frusto-conical surface 43. The relative strengths of the spring 101 and the springs 40 are such that while the springs 40 bias the slips inwardly and upwardly along the expander surface 43, the spring 101 acting through the springs 40 overcomes the springs 40 to an extent sufficient to maintain the lower ends of the slip lugs 82 against the surfaces 102 of the operator sleeve defining the lower ends of the windows 45 until the slips move into contact with the inner surface 29 of the tubing 30.

The seal assembly 31 includes an annular flexible sealing element 103 of synthetic rubber or other suitable material moulded around upper and lower ring-shaped anti-extrusion members 104. The sealing element has a normal outside diameter somewhat smaller than the internal diameter of the tubing string so that it will pass readily through the bore of a tubing string in which the anchoring and sealing device is to be installed. The sealing element is generally tubular in shape having a bore 105 which is enlarged along its central portion to provide an internal annular recess 106. The upper end of the bore of the sealing element is flared outwardly at 110 and the lower end of the bore is likewise flared outwardly at 111. The sealing element is confined on the middle mandrel section 22 between an upper end section 112 of the bottom mandrel section 24 and an external annular flange 113 of an expander sleeve 114 which fits in sliding relationship around the middle section 22 extending above the sealing element into the operator sleeve 50. The expander sleeve has a plurality of upwardly extending fingers 114a which are sufficiently flexible to spring in

wardly to facilitate engagement of the expander sleeve within the operator sleeve.

An internal annular recess 115 is formed within the flange 113 to receive an O-ring 120 and a spacer ring 121 which has at least one radially or laterally extending flow passage 121a to permit fluid to flow from around the mandrel into the annular recess 115 around the outside of the O-ring 120 so that fluid pressure around the mandrel below the O-ring is communicated to the outer surfaces of the O-ring and tends to force the O-ring inwardly around the mandrel effecting a seal between the mandrel and the upper end surface of the recess 115 to prevent upward fluid flow past the O-ring along the mandrel. Pressure along the mandrel above the O-ring, however, tends to displace the O-ring outwardly farther into the annular recess 115. Fluid may thus flow downwardly past the O-ring 120 when the pressure above the O-ring exceeds the pressure therebelow but may not flow upwardly along the mandrel past the O-ring when the pressure below the O-ring exceeds the pressure thereabove.

The lower end outer surface 122 of the flange 113 is inclined inwardly and downwardly connecting with an annular frusto-conical depending wedge surface 123 on the lower end section of the expander 114 to engage the upwardly and outwardly flared surface 110 of the sealing element 103 whereby fluid pressure from above the sealing element may displace the upper portion of the element outwardly and flow within the bore of the element into its annular recess 106.

An internal annular recess 124 is formed within the upper end section 112 of the bottom sub 24 to receive the O-ring 125 and the spacer ring 130. The spacer ring has at least one radially extending passage 131a whereby the combination with the O-ring 125 functioning in the same way as the O-ring 120 and the spacer ring 121 prevents downward flow along the external surface of the lower mandrel past the O-ring while upward flow from below the O-ring along the surface of the mandrel is permitted.

The upper end surface 131 of the bottom section is inclined upwardly and inwardly connecting with an upwardly extending annular frusto-conical wedge surface 132 on the upper end section 112 of the bottom section which engages the flared surface 111 of the sealing element 103 to allow fluid flow from below the sealing element to displace the lower portion of the sealing element outwardly and flow into internal annular recess 106 of the sealing element. When pressure below the sealing element exceeds the pressure thereabove, pressure from below the sealing element 103 enters the bottom mandrel section through a lateral port 133, passes upwardly through an annular space 134 between the bottom mandrel and the middle mandrel section above the port 133. The fluid pressure from below the sealing element 103 displaces the O-ring 125 away from the lower mandrel and is communicated past the frusto-conical section 132 into the internal annular recess 106 expanding the sealing element against the surface surrounding the sealing element. Similarly, when pressure above the sealing element exceeds the pressure therebelow, the pressure thereabove, which is communicated to the upper inner surfaces of the upper O-ring 120 through any spaces between the mandrel and the expander sleeve 114, moves the O-ring out of sealing engagement with the mandrel. The fluid pressure is thus communicated past the frusto-conical surface 123 into the annular recess 106 and expands the sealing element. The sealing element is thereby adapted to seal against a fluid pressure differential across the element with a higher pressure either above or below the element tending to improve its sealing relationship with an adjacent surrounding surface with which it is sealing. The seal assembly 31 is described, illustrated, and claimed in a copending United States patent application of the inventor, Ser. No. 374,046.

Each of the upwardly extending flexible fingers 114a of the expander sleeve 114 has an external boss 140 at its free end providing a downwardly facing external shoulder 141 which is engageable with an internal annular flange 142 formed at the lower end of the operator sleeve 50 to hold the expander sleeve 114 against downward movement relative to the operator sleeve. Each of the fingers 114a also is provided with an internal upwardly and inwardly facing shoulder 143 engageable with an external annular shoulder 144 formed around the middle section 22 to limit the upward movement of the expander sleeve on the mandrel. The flexibility of the fingers 114a permits them to be cammed inwardly so that the bosses 140 pass within the internal flange 142 to facilitate engaging the expander sleeve within the operator sleeve.

The operator sleeve 50 is telescoped over the middle mandrel section 22 and the expander sleeve 114 and is provided with an internal annular flange 150a providing an upwardly facing shoulder 145 which is engageable with an external downwardly facing annular shoulder 150 around the middle mandrel section to limit the upward movement of the operator sleeve relative to the mandrel. An internal annular recess 151 is formed in the bore of the operator sleeve below the flange 150a and communicates with a larger internal annular recess 152. The internal annular upwardly and inwardly extending cam shoulder 153 defines the upper end of the recess 152 between the connecting recesses 151 and 152.

A plurality of lock segments 154 are confined within the annular recess 152 between the annular shoulder 153 and the upper end 155 of the expander sleeve 114. The lock segments are substantially rigid members which may be either metal balls or short segments of a metal ring having an internal diameter approximately equal to the external diameter of the middle mandrel below the shoulder 144 and an external diameter slightly less than the diameter of the annular recess 151. The lock segments are circumferentially spaced around the mandrel with a sufficient number being employed to permit even application of force from the operator sleeve 50 to the upper end of the expander sleeve 114 through the lock segments. The lock segments are held radially outwardly in the recess 152 by the outer surface 160 of the middle mandrel and are confined longitudinally between the cam shoulder 153 of the operator sleeve and the upper ends 155 of the fingers 114a. The internal annular flange 142 of the operator sleeve is engaged with the downwardly facing shoulders 141 of the fingers 114a. The operator sleeve and the expander sleeve are thus longitudinally interlocked with each other. The operator sleeve, the lock segments, and the expander sleeve move downwardly together until the lock segments reach the shoulder 144 whereupon the lock segments are cammed inwardly by the shoulder 153 around the smaller diameter middle mandrel surface 161 releasing the operator sleeve to telescope farther downwardly over the expander sleeve with the internal surface of the operator sleeve defining the recess 151 passing downwardly over the lock segments to hold them around the surface 161.

The operator sleeve 50 is provided with two access holes 170 circumferentially spaced apart 180 degrees around the sleeve to correspond with the circumferentially spaced blind radial holes 171 extending into the middle section 22. During assembly of the anchoring and sealing device a suitable spanner wrench, not shown, having an inwardly extending lug is engaged on the operator sleeve with its lug extending through one of the holes 170 and into one of the blind holes 171 to hold the middle mandrel section against rotation relative to the operator sleeve to facilitate making the necessary threaded connections for assembly of the device.

The fishing neck 33 is provided at its upper end with an external annular flange 180 forming a downwardly facing external annular shoulder 181 for engagement of

a suitable fishing tool utilized in unlocking and removing the device from a tubing string, as will be explained hereinafter. An upper end section 180 of the upper mandrel section 21 is enlarged providing a downwardly facing external annular shoulder 191. External tangentially extending recesses 192 are formed in the upper end section of the upper mandrel to receive shear pins employed in the connection of a running tool with the anchoring and sealing device. The bore of the upper mandrel is enlarged along an upper end section 193 providing an upwardly facing internal annular shoulder 194 which provides a seat surface to limit downward movement of a well tool, such as a choke or similar apparatus, not shown, which may be supported by the device 20 during its operation within a well.

FIGURE 5 illustrates a running tool 200 which is secured in telescopic relationship over the fishing neck 33 and the upper end section 190 of the upper mandrel 21 for supporting the device 20 during installation and for actuating the slip assembly 28 and the seal assembly 31 to engage the device in a tubing section. The running tool has an upper threaded pin section 201 for securing the tool in the lower end of a wire line tool string as illustrated and described at page 3742 of the Composite Catalog of Oilfield Equipment & Services, 1964-65 edition, published by World Oil, Houston, Texas. The running tool includes a sleeve section 202 which is provided with a downwardly opening bore having an upper section 203 adapted to fit in sliding relationship over the upper end section 190 of the upper mandrel of the device 20 and a larger lower bore section 204 which fits in sliding relationship over the external annular flange 180 of the fishing neck 33 on the device 20. An internal annular downwardly and inwardly facing shoulder 205 is formed within the sleeve 202 at the junction of the bore sections 203 and 204. The lower end surface 210 of the sleeve 202 is engageable with the upwardly facing external annular shoulder 33a around the fishing neck to limit the downward movement of the sleeve 202 over the fishing neck. An internal annular shoulder 211 is formed within the sleeve 202 at the upper end of the bore section 203 to engage the upper end 190a of the upper mandrel 21 to limit the downward movement of the sleeve over the mandrel. The sleeve 202 is provided with two tangentially extending holes 212 which are circumferentially spaced 180 degrees around the sleeve from each other and intersect the bore section 203 forming two internal tangential recesses 213 each of which receives a shear pin 214 to interlock the running tool with the device 20. Each shear pin is inserted through a tangential hole 212 of the operator sleeve and extends through a recess 213 of the operator sleeve and a tangential recess 192 in the upper end section of the upper mandrel 21 for locking the running tool on the upper end section in telescopic relationship over the anchoring and sealing tool 20 as shown in FIGURE 5. The holes 215 extend through the sleeve 202 of the running tool downwardly and inwardly from the base of the reduced head section 220 into the bore section 203 to permit fluid communication through the running tool with the bore 32 of the device 20 for relieving any pressure differential which might develop across the anchoring and sealing device when inserting the device into and removing it from a fluid-filled tubing string.

One application of the anchoring and sealing device 20 is as a component of a pack-off anchor assembly within a tubing string to straddle and pack-off a hole or holes in the tubing so that fluid-flow may be continued through the tubing without removing and replacing the tubing. One such pack-off assembly is illustrated and described at page 3678 of the Composite Catalog and Oilfield Equipment & Services, supra. In the installation shown in the reference the anchoring and sealing tool 20 is substituted for the "top type G Otis pack-off assembly." The "type D Otis collar stop lock" is first run into the well on a

suitable wire line tool string and locked in the first collar connection within the tubing string below the holes to be isolated by the pack-off assembly. The "bottom type G Otis pack-off assembly" is then connected on the lower end of the spacer pipe and the anchoring and sealing device 20 is secured on the upper end of the spacer pipe by a suitable pipe coupling threaded on the lower end of section 34 of the bottom mandrel section 24 of the device 20. The running tool 200 shown in FIGURE 5 is then telescopically engaged over the upper mandrel section 21 and the fishing neck 33 until the lower end 210 of the running tool sleeve engages the upper shoulder 33a of the fishing neck. The shear pins 214 are inserted through the holes 212 and the recesses 213 within the running tool sleeve and 192 of the upper end section of the upper mandrel 21 to interlock the running tool and the device 20.

The running tool is connected by means of the threaded pin 201 to a suitable wireline tool string and lowered in the tubing string 30. During the lowering of the device 20 the fishing neck 33 remains in the upper position illustrated in FIGURE 1 due to the operative interconnection between the running tool and the upper mandrel 21 which is held against longitudinal movement in the running tool by the shear pins 214. The lower end of the sealing element 103 now bears against the upper end of the bottom mandrel section. The expander sleeve 114 is resiliently supported against downward movement by the upper end of the sealing element 103 while the operator sleeve 59 is interconnected with the expander sleeve by the lock segments 154. The fishing neck is threaded into the upper end of the operator sleeve holding the fishing neck in its upper position since the weight of the expander sleeve, the operator sleeve, and the fishing neck is not sufficient to compress the sealing element.

The slip assembly 28 is held in the retracted position shown in FIGURE 1 by the engagement of the lower end of each slip tongue 32 with the operator sleeve surface 102 defining the lower end of its respective lateral window 40. The operator sleeve is supported in an upper position as described above. The hairpin springs 40 hold the slips, the slip operators 42, and the slip shoes 41 inwardly around the upper mandrel 21 and the expander surface 43 while the spring 101 bearing against the upper ends 91 of the springs 40 bias the slips and associated members downwardly along the mandrel and expander surfaces with the slips being held against the surfaces 102.

The assembly including the anchoring and sealing device 20, the "spacer pipe," and the "bottom type G Otis pack-off assembly" is lowered on the wireline tool string until the lower end collet fingers of the bottom pack-off assembly engage the internal fishing neck in the upper end of the collar stop lock. When the bottom pack-off assembly is engaged with the collar stock lock the bottom pack-off assembly is held by the stop lock against downward movement so that further downward force exerted by the wireline tool string thereto through the mandrel 20a of the device 20 expands the sealing element of the bottom pack-off assembly. The seating of the bottom pack-off assembly against the stop lock holds the pack-off assembly against downward movement while the force is being exerted by the tool string against the running tool 200 to sever the shear pins 214. The mandrel 20a is now held against downward movement by virtue of its rigid connection with the spacer pipe which is held against downward movement by the bottom pack-off assembly engaged with the collar stop lock.

After the pins 214 have been sheared, the mandrel of the tool 20 remains held against downward movement for the reasons just explained while the released sleeve 202 of the running tool 200 telescopes downwardly over the upper mandrel section 21 and the lower end 210 of the running tool engages the shoulder 33a on the fishing neck 33 forcing the fishing neck in a downward direction relative to the upper mandrel section. As the fishing neck

moves downwardly, the operator sleeve 50 is also forced downwardly. The interconnection of the expander sleeve 114 and the operator sleeve 50 through the lock segments 154 causes the expander sleeve to move downwardly with the operator sleeve. As the expander sleeve 114 moves downwardly the lower end surface 122 of the sleeve engages the upper end of the sealing element 103 to compress the element and expand it radially while its lower end is held by engagement with the upper end surface 131 of the bottom sub 24. The outer surface of the sealing element engages and seals with the inner surface 29 of the tubing 30 as shown in FIGURE 6.

The operator sleeve 50 acting through the lock segments 154 forces the expander sleeve downwardly until the lock segments reach the annular shoulder 144 on the lower mandrel at which time the annular cam shoulder 153 of the operator sleeve cams the lock segments inwardly around the surface 161 of the middle mandrel and out of the internal annular recess 152 releasing the operator sleeve for downward movement over the expander sleeve and locking the expander sleeve in the lower position shown in FIGURE 6. The sealing element 103 is expanded sufficiently to effect a fluid tight seal with the tubing but is not overcompressed or overexpanded. The inner surface of the operator sleeve defining the recess 151 holds the lock segments radially inwardly around the reduced section 161 of the middle section 22 and the segments are confined longitudinally between the downwardly facing annular shoulder 144 on the middle section and the upper ends 155 of the expander sleeve fingers 114a holding the expander sleeve against upward movement and locking the sealing element 103 in radially expanded sealing relationship with the tubing inner surface 29.

Preferably, the slip assembly 23 and the seal assembly 31 are so interrelated that when the lock segments 154 move out of the recess 152 the sealing element is in fluid tight engagement with the tubing surface and the slips 35 are expanded laterally sufficiently to make initial contact with the tubing surface. When the above described downward movement of the locking sleeve 50 is initiated, the surface 70 defining the upper end of the window 45 in the operator sleeve engages the upper end 65 of each slip operator 42 to move the operator downwardly with the operator sleeve. The springs 40 bias the slips inwardly with sufficient force that the frictional resistance against sliding between adjacent surfaces of each slip and its operator and slip shoe causes them to move simultaneously as a unit downwardly and outwardly along the expander surface 43 until the slip teeth contact the tubing surface. The areas of the adjacent contacting surfaces of the slip operators and the slips and slip shoes are greater than the contact areas between the slip shoes and the expander surface 43 so that the smaller area of surface contact between each slip shoe and the expander surface permits each slip shoe to slide along the expander surface with no relative longitudinal motion occurring between each slip and its operator and slip shoe. During initial expansion of the slips until they engage the tubing surface the spring 101 is not compressed since there is no relative longitudinal movement between the operator sleeve and each slip. During the initial movement of the slip assembly in its expansion from the position shown in FIGURE 1 to the position of FIGURE 6 the lower end of each slip remains in engagement with the surface 162 defining the lower end of the window 45 in the operator sleeve 50. As the operator sleeve moves downwardly, the inner conical surface of each slip shoe moves along the expander surface 43 to move each shoe and its operator and slip radially outwardly. With the lateral expansion of each shoe, operator, and slip, the fragmentary cylindrical surfaces 52 and 62 of each slip shoe and operator, respectively, move laterally away from the outer surface of the upper mandrel 21 to the spaced apart position shown in FIGURE 6. Thus, when the initial phase of the downward movement of the operator sleeve 50 is completed, the slips are expanded outwardly into initial contact with the inner

wall of the tubing and the sealing element 103 is expanded and locked in expanded position by the lock segments 154 which are held between the shoulder 144 and the upper ends 155 of the fingers 114a on the expander sleeve 114.

With the lock segments 154 cammed inwardly by the surface 153 releasing the operator sleeve 50 to move farther downwardly, a further downward force transmitted from the running tool through its lower end 210 against the upper shoulder 33a of the fishing neck 33 forces the operator sleeve farther downwardly to continue the expansion of the slips into locking engagement with the tubing. The downward force applied to the operator sleeve is transmitted to the upper end 65 of each slip operator 42 through the respective surface 70 of the operator sleeve defining the upper end of the window 45 in which the operator is positioned. The downward force of the operator sleeve wedges each slip operator between the back surface of its slip and the outer surface of its slip shoe. The teeth 81 on each slip engage the wall of the tubing holding the slips against downward movement along the tubing as the resistance against downward movement of the slips due to the teeth biting into the tubing wall is greater than the friction between each slip and its operator while the operator is wedged between the slip and the slip shoe. Therefore, each slip operator is driven downwardly between its slip and slip shoe expanding each slip farther outwardly to firmly engage the tubing. The downward movement of the operator sleeve 50 over the mandrel sections is limited by the running tool 200. The running tool forces the fishing neck 33 downwardly about the upper mandrel section until the internal annular shoulder 211 within the running tool sleeve 202 engages the upper end 196a of the upper mandrel section. As the operator sleeve and the slip operators move downwardly and each slip is held against downward movement wedging its operator between it and its slip shoe, the operator sleeve thus moves downwardly relative to the slips so that the lower end surface 102 of the operator sleeve window 45 moves downwardly to a position below the lower ends of the slips as illustrated in FIGURE 7. The lip 83 on each slip engages its respective slip shoe to hold the shoe against downward movement as its slip operator is wedged between the slip and the shoe. The wedging of the operator member between the slip and the shoe effects the lateral expansion of the slip moving the slip farther away from the slip shoe as shown by comparison of FIGURES 6 and 7. The longitudinal space between the upper end of each slip and the flange 64 on its operator is substantially closed by the downward movement of the operator relative to the slip. The length of each slip operator is preferably such that its slip will be fully expanded prior to engagement between the flange 64 on the operator and the upper end of the slip.

As the operator sleeve 50 moves downwardly after release by the inward movement of the lock segments, the operator sleeve telescopes downwardly over the expander sleeve to the position shown in FIGURE 7. The lower end of the operator sleeve does not engage the flange 113 on the expander sleeve and therefore does not move the expander sleeve downwardly. The seal element 103 thus is mechanically expanded and locked in the expanded state when the lock segments release the operator sleeve.

During the downward movement of the fishing neck 33 and the operator sleeve 50 between the positions of FIGURES 6 and 7 while the operator members are being wedged behind the slips and the slips are held against longitudinal movement, the fishing neck telescopes farther downwardly over the upper end 91 of each spring 40 compressing to the spring 101 farther into the annulus 100. In its compressed state as shown in FIGURE 7 spring 101 supplies a substantial downward force to the springs 40 biasing the slips downwardly and outwardly along the outer surfaces 75 of the slip operator members providing a constant expanding force to the slips to resist

any tendency for them to disengage from the tubing surface.

FIGURE 7 illustrates both the slip assemblies 28 and the sealing assembly 31 in their fully expanded positions within the tubing. An upward force exerted against the bottom sub 24, the sealing assembly, or the mandrel, is transmitted to the slip assembly wedging the slips into tighter engagement with the tubing. The frusto-conical expander surface 43 on the middle section transmits the upward force to the downwardly and inwardly sloping fragmentary conical surfaces on the slip shoes, the slip operators and the inner surfaces of the slips forcing the slips outwardly more tightly against the tubing. Simultaneously, the force from the compressed spring 101 acting through the hairpin springs 40 urges the slips along the downwardly and outwardly tapered surfaces 75 of the slip operators into tighter engagement with the tubing wall.

Fluid pressure below the sealing element 103 is applied through the port 133 into the annular space 134 displacing the O-ring 125 outwardly in the recess 124 allowing the pressure to pass upwardly into the annular recess 106 of the sealing element 103 further expanding the sealing element against the inner tubing surface 29. The pressure from below the sealing element also is transmitted along the middle mandrel upwardly through the bore 106 of the sealing element, within the flange 113, and outwardly into the annular recess 115 through the radial flow passages in the spacer ring 121. The pressure in the recess 115 forces the O-ring 120 inwardly and upwardly and against the mandrel and the annular surface of the expander sleeve defining the upper end of the recess 115 to seal the space between the mandrel and the bore through the expander sleeve 114. Thus, when the pressure below the sealing element exceeds the pressure above it the sealing element is further expanded and the pressure is transmitted only up to the O-ring 120.

When the pressure above the sealing element 103 exceeds the pressure below the element the pressure passes the O-ring 120 into the annular recess 106 within the sealing element to further expand the element outwardly against the tubing wall. The higher pressure from above the sealing element is prevented from moving downwardly along the middle mandrel beyond the O-ring 125 as the pressure moves through the lateral passages in the spacer ring 130 to urge the O-ring inwardly around the middle mandrel sealing between the mandrel and the bore through the upper end section of the bottom mandrel.

The seal assembly 31 is therefore effective to seal against a pressure differential from either above or below the seal assembly while the slip assembly 30 is "self-energizing" in that a force increase against the seal and the mandrels tending to move them upwardly tends to further expand the slips against the wall of the tubing.

When the expansion of the seal assembly 31 and the slip assembly 28 is completed in the above described manner the wireline tool string is lifted in the tubing string raising the running tool 200 from the top of the tool 20. Since the pins 214 were sheared prior to expansion of the seal element 103 and the setting of the slips of the tool, the sleeve 202 of the running tool is not held against upward movement relative to the device 20 and thus may easily be lifted from the top of the device. The device 20 then remains locked within the tubing until it is desired to remove it.

To remove the device 20 from the tubing, a suitable pulling tool such as an Otis type RJ pulling tool shown at page 3746 of the Composite Catalog of Oilfield Equipment & Services, supra, is engaged on a wireline tool string. The pulling tool engages the shoulder 181 of the fishing neck 33 so that an upward movement imparted to the pulling tool causes the fishing neck to move upwardly to lift the operator sleeve 50 which initially moves upwardly from the position shown in FIGURE 7. When the lower end of the recess 151 moves above the lock

segments 154 they are cammed outwardly into the recess 152 due to their engagement with the upwardly and outwardly extending shoulder 144 of the middle mandrel section by the upward force applied from the compressed sealing element 103 acting through the expander sleeve 114. The upper ends of the fingers 114a force the lock segments against the upwardly and outwardly sloping shoulder 144 causing the lock segments to be cammed outwardly into the recess 152 which has now moved into alignment with the lock segments with the shoulder 153 being slightly above the lock segments so that the segments may move radially outwardly into the recess 152. At about the same time, the upwardly facing shoulder provided by the internal flange 142 of the operator sleeve 50 engages the downwardly facing shoulder 141 on the fingers 114a and further lifting of the operator sleeve 50 lifts the expander sleeve 114 allowing the sealing element 103 to expand longitudinally and contract radially inwardly away from the tubing wall. Fluid trapped in the cavity of the seal 103 escapes between the seal and the frusto-conical surfaces 123 or 132.

As the locking sleeve is lifted to relieve the force on the seal element 103, the slip assembly 28 is also being retracted from the tubing. The lugs 71 and 72 on each of the slip operators are received, respectively, in the recesses 73 and 74 of the side windows in the operator sleeve so that upward movement of the sleeve lifts each of the slip operators to disengage them from their wedged position between the slips and the slip shoes. When the operator sleeve is at the longitudinal position that the lock segments 154 are cammed outwardly into the recess 152 to release the seal element 103, the slip operators are lifted to the position illustrated in FIGURE 6. The lifting of the fishing neck 33 by the fishing tool also raises the internal shoulder 33b at the upper end of the annulus 180 allowing the spring 101 to expand reducing the force of the spring 101 against the upper ends of the hairpin springs 40 so that the hairpin springs may retract the slips inwardly to the positions shown in FIGURE 6. When the fishing neck and the operator sleeve have been moved upwardly to the position of FIGURE 6, the slips are retracted sufficiently that they are either just slightly touching the wall of the tubing or are spaced apart from the wall and no longer in locking relationship with the tubing. The lower end surfaces 102 of the window 45 of the operator sleeve are each engaging the lower end of its respective slip. The upward force applied by the fishing tool on the fishing neck is continued, lifting the fishing neck and the operator sleeve upwardly until the upwardly facing shoulder 145 of the operator sleeve 50 engages the annular shoulder 150 of the middle mandrel section 22 as shown in FIGURE 1. The upward movement of the operator sleeve from the position shown in FIGURE 6 back to the position of FIGURE 1 forces the slips and their operators and shoes upwardly along the expander surface 43 and the springs 40 move them to the positions of FIGURE 1 so that the slips are fully retracted into the side windows of the operator sleeve and the anchoring and sealing device 20 is completely released from the tubing and may be lifted by the fishing tool back to the surface. With the device 20 thus released from the tubing, the force on the fishing tool will lift the device, the spacer pipe, and the bottom pack-off assembly upwardly, the seal assembly of the bottom pack-off assembly relaxing away from the tubing wall and the collet fingers of the bottom pack-off assembly and the collar stop lock disengaging so that the entire assembly from the device 20 down through the bottom pack-off assembly is lifted at the same time to the surface leaving the collar stop lock engaged in the tubing.

It will now be seen that a new and improved anchoring and sealing device has been illustrated and described.

It will also be seen that the device includes "pressure-energized" slips which are expandable into tighter relationship with a surrounding engaged surface by a force

acting in the same direction as a force employed to release the slips from the surrounding surface.

It will also be seen that the anchoring and sealing device includes a slip assembly having members with adjacent fragmentary conical surfaces which are fully seated with each other when the slips are expanded to the maximum extent permitted by the surrounding surface with which they are engaged.

It will also be seen that the fragmentary conical surfaces of the components of the slip assembly are only partially seated with each other when the slips are retracted to the normal position at which they are located for inserting the device into and removing it from a tubing section.

It will additionally be seen that each slip along with its slip operator and slip shoe moves longitudinally as a unit during the initial phases of locking the anchoring and sealing device within a tubing section while the slips are expanded laterally or radially away from the slip shoes during the latter phases of locking the device in the tubing.

It will also be seen that the slip assembly of the anchoring and sealing device includes slip operators which are initially moved longitudinally to simultaneously move each slip and its slip shoe along an expander surface, are wedged longitudinally between each slip and its shoe to laterally expand each slip away from its shoe to complete the locking of the device with a surrounding surface, and when longitudinally withdrawn from wedging engagement between each slip and its shoe permits lateral retraction of the slips by hairpin retainer springs.

It will be further seen that the slip assembly of the anchoring and sealing device includes expandable slips which are supported on a frusto-conical expanding surface by laterally operable hairpin springs connected between the slips and biased toward the expanding surface by a longitudinally operable spring.

It will additionally be seen that the anchoring and sealing devices includes a slip assembly having slips which are expanded into tighter engagement with a surrounding surface by an upward force on the mandrel supporting the slip assembly and also are released by an upward force applied to the fishing neck of the device.

It will be further seen that the anchoring and sealing device includes an annular sealing element which is initially mechanically expanded into sealing relationship with a surrounding surface and which subsequently is further expanded by fluid pressure applied either above or below the sealing element.

It will be also seen that the anchoring and sealing device may serve as a component of a pack-off assembly for isolating leaks in a section of tubing to reestablish fluid flow through the tubing to bypass the leaking section.

It will also be seen that the anchoring and sealing device may function to limit the upward movement of and seal above a well tool secured to the lower end of the anchoring and sealing device.

The foregoing description of the invention is explanatory only, and changes in the details of the construction illustrated may be made by those skilled in the art, within the scope of the appended claims, without departing from the spirit of the invention.

What is claimed and desired to be secured by Letters Patent is:

1. An anchoring and sealing device comprising: mandrel means; external annular sealing means supported on said mandrel means for radial expansion to seal with a surface surrounding said mandrel means responsive to longitudinal force applied to said sealing means, said sealing means being adapted to be initially mechanically expanded radially to engage said surface and subsequently to be further expanded hydraulically responsive and proportional to fluid pressure applied longitudinally to said seal element from above or below said element; and slip

means supported on said mandrel means for releasably engaging said surrounding surface to hold said device against longitudinal movement relative to said surface against a force applied to said mandrel means in a first direction, said slip means being adapted to expand into tighter locking relationship with said surface responsive to a force applied to said mandrel means in said first direction, said slip means including means adapted for longitudinal movement responsive to a force applied in said first direction; and means supported on said mandrel means for longitudinal movement for expanding and contracting said slip means and actuating said sealing means.

2. An anchoring and sealing device comprising: mandrel means; external annular sealing means supported on said mandrel means for radial expansion responsive to longitudinal mechanical force and fluid pressure applied across said means from above or below said means to seal with a surface surrounding said mandrel means; slip means supported on said mandrel means for releasably engaging said surrounding surface to hold said device against longitudinal movement in a first direction relative to said surface, said slip means being adapted to be urged into tighter locking engagement with said surrounding surface responsive to a force on said mandrel means in said first direction; retainer means for yieldably holding said slip means radially inwardly around said mandrel means; and yieldable compressible means adapted to bias said slip retainer means in a direction to expand said slips.

3. An anchoring and sealing device comprising: mandrel means having a slip expander surface sloping inwardly in a first direction toward said mandrel means; slip means supported on said expander surface for longitudinal movement along said expander surface for releasably engaging a surface surrounding said device to releasably hold said device against longitudinal movement relative to said surrounding surface; yieldable retainer means for holding said slip means on said expander surface; means operatively engaged with said retainer means for biasing said slip means in a second longitudinal direction along said expander surface; slip operator means for expanding said slips responsive to a force applied in said second direction and for retracting said slips to release said device from said surrounding surface responsive to a force applied in said first direction; and external annular sealing means adapted for radial expansion responsive to longitudinal mechanical force and fluid pressure applied across said sealing means from above or below said means.

4. An anchoring and sealing device comprising: mandrel means; external annular sealing means supported on said mandrel means for radial expansion to seal with a surface surrounding said mandrel means; said mandrel means having a slip expander surface sloping in a first direction inwardly toward said mandrel means; longitudinally slideable slip means supported on said expander surface for releasably engaging said surface surrounding said mandrel means to lock said device against longitudinal movement relative to said surrounding surface; means for supporting said slips on said expander surface and for biasing said slips toward said expander surface; means for biasing said slips along said expander surface in a second direction; slip operator means operatively engaged with said slip means for moving said slip means in said second direction along said expander surface, said operator means being movable in said first direction to release said slip means from said surrounding surface; and sleeve means slidably supported around said mandrel means engageable with said slip operator means, said slip means, and said sealing means for expanding and releasing said sealing means and for expanding and contracting said slip means.

5. An anchoring and sealing device comprising: mandrel means having a slip expander surface sloping inwardly in a first direction; external annular sealing means supported on said mandrel means for radial expan-

sion to seal with a surrounding surface around said mandrel means; slip means supported on said expander surface for longitudinal movement relative thereto to releasably engage said device with said surrounding surface to hold said device against longitudinal movement relative to said surface; first spring means connected with said slip means for biasing said slip means inwardly around said expander surface; second spring means operatively engageable with said first spring means for biasing said slip means along said expander surface away from said mandrel means; operator means adapted for longitudinal movement relative to said mandrel means for moving said slip means along said expander surface away from said mandrel means and releasing said slip means for inward movement toward said expander surface; and sleeve means slidably supported on said mandrel means operatively engageable with said seal means for expanding end permitting retraction of said seal means and engageable with said operator means for expanding and retracting said slip means.

6. An anchoring and sealing device comprising: mandrel means; external annular sealing means supported on said mandrel means for radial expansion to seal with a surface surrounding said mandrel means, said sealing means being adapted for mechanical expansion to effect an initial fluid tight seal with said surrounding surface and for further expansion responsive to a fluid pressure differential applied across said sealing means from above or below said means; said mandrel means having an expander surface sloping in a first direction toward said mandrel means; slip means supported on said expander surface for movement in a first longitudinal direction for retracting said slips and for movement in a second direction for expanding said slips into releasable engagement with said surrounding surface; spring retainer means operatively engaged with said slip means for supporting said slip means on said expander surface and biasing said slip means inwardly toward said surface; second spring means operatively engaged with said first spring means for biasing said slip means along said expander surface in said second direction; operator means engaged between said slip means and said mandrel means for movement in said second direction to expand said slip means and for movement in said first direction to release said slip means from locking relationship with said surrounding surface; and sleeve means longitudinally slidably supported around said mandrel means for engagement with said sealing means to expand said sealing means and release said sealing means for contraction around said mandrel means, said sleeve means being engageable with said operator means and said slip means for expanding and contracting said slip means.

7. An anchoring and sealing device comprising: a mandrel; an external annular sealing element supported around said mandrel to seal with a surface surrounding said mandrel, said sealing element being adapted to be initially mechanically expanded into fluid tight relationship with said surrounding surface and subsequently further expanded by a fluid pressure differential applied across said sealing element from above or below said element; said mandrel having an expander surface sloping toward the longitudinal axis of said mandrel away from said sealing element; a plurality of slip shoes supported around said mandrel for longitudinal movement along said expander surface; a slip operator supported on each of said slip shoes for longitudinal movement relative thereto; a slip supported over each slip operator and slip shoe for movement relative to said operator and said shoe for releasably engaging said surrounding surface to hold said device against longitudinal movement thereto; laterally operable retainer springs engaged between said slips for holding said slips on said expander surface and biasing said slip, said operators, and said slip shoes toward said expander surface; a longitudinally operable spring operatively associated with said slip retainer springs for biasing said slips along said expander surface toward an expanded

condition; and sleeve means supported on said mandrel for longitudinal movement relative thereto, said sleeve means being operatively engageable with said annular sealing element for expanding said sealing element and releasing said element and being engageable with said slip operators and said slips for expanding and contracting said slips along said expander surface on said mandrel.

8. An anchoring and sealing device comprising: a mandrel having an upwardly and inwardly sloping slip expander surface; an external annular sealing element supported on said mandrel below said expander surface; a plurality of slip shoes supported on said expander surface for longitudinal movement relative thereto; a slip operator supported on each of said slip shoes for longitudinal movement with and relative to each said slip shoe; a slip supported on each slip operator and corresponding slip shoe; laterally operable retainer springs connected between corresponding sides of said slips for retaining said slips with corresponding slip operators and slip shoes on said expander surface; a longitudinally operable spring positioned around said mandrel having a lower end engaged with said retainer springs for biasing said retainer springs downwardly relative to said expander surface; a sleeve positioned around said mandrel; means operatively connected with said sleeve and engageable with said annular sealing element for expanding and permitting contraction of said sealing element around said mandrel, said sleeve having lateral windows for receiving said slips, slip operators, and slip shoes to permit lateral expansion of said slips through said window, the surface defining the upper end of each of said windows being engageable with the upper end of the slip operator positioned within said window for moving said operator downwardly relative to said mandrel to expand the slip associated with said operator and the surface defining the lower end of each of said lateral windows of said sleeve being engageable with the lower end of the slip positioned within said window for engaging and moving said slip upwardly along said expander surface to retract said slip; and a fishing neck slidably engaged over said mandrel, said fishing neck being connected with the upper end of said sleeve and being provided with an internal downwardly opening annular recess for receiving said longitudinally operable spring.

45. An anchoring and sealing device comprising: an upper mandrel section; a middle mandrel section connected on a lower end section of said upper mandrel section, said middle mandrel section having an external upwardly and inwardly sloping frusto-conical expander surface along an upper end section thereof; a lower mandrel section secured on a lower end section of said middle section, an external annular sealing element positioned on said middle and lower mandrel sections below said expander surface, said sealing element being held against downward movement on said mandrel section and being adapted to be longitudinally compressed for radial expansion to seal with a surface surrounding said mandrel; an expander sleeve slidably positioned on said middle mandrel section above said sealing element for applying a longitudinal downward force to the upper end of said sealing element to expand said sealing element; a plurality of slip shoes supported around said upper mandrel section and said expander surface of said middle mandrel section for sliding movement downwardly along said expander surface; a slip operator supported on each of said slip shoes for sliding movement relative to said slip shoe; a slip having an external toothed surface supported on each of said slip operators and its associated slip shoe for releasably engaging a surface surrounding said mandrels; 70 laterally operable slip retainer springs secured between said slips for retaining each of said slips and its associated slip operator and slip shoe on said expander surface and said upper mandrel, each of said springs extending between corresponding sides of said slips; a longitudinally operable spring positioned around said upper mandrel

having a lower end engaged with said slip retainer springs for biasing said retainer springs downwardly; an operator sleeve positioned around said upper and middle mandrel sections adapted to move longitudinally over said mandrel sections; locking means operatively interconnecting the lower end of said operator sleeve and said expander sleeve for expanding said sealing element responsive to downward movement of said operator sleeve and for locking said sealing element in expanded relationship after downward movement of said operator sleeve a predetermined distance; said operator sleeve having lateral windows each of which receives one of said slips and an associated slip operator and slip shoe to permit lateral expansion and contraction of said slips around said mandrels through said windows; a surface defining the upper end of each of said lateral windows in said operator sleeve engageable with the upper end of the slip operator positioned within said window for moving said slip operator downwardly responsive to downward movement of said operator sleeve; a lower surface defining the lower end of each of said lateral windows engageable with the lower end of the slip positioned within said window for moving each of said slips upwardly and inwardly along said expander surface responsive to upward movement of said sleeve; and a fishing neck slidably positioned over said upper mandrel connected with the upper end of said operator sleeve, said fishing neck having a downwardly opening internal annular recess to receive said longitudinally operable spring, the upper end of said spring being engageable with a downwardly facing surface defining the upper end of said internal annular recess for compressing said spring responsive to downward movement of said fishing neck and said operator sleeve to bias said slip retainer springs downwardly.

10. An anchoring and sealing device in accordance with claim 9 wherein adjacent mating surfaces of said slip expander surface, said slip shoes, said slip operators and said slips are frusto-conical in shape and formed to fully mate each with the other when said slips are fully expanded into engagement with a surface surrounding said device and said surfaces are mismated from each other when said slips are in retracted position.

11. An anchoring device comprising: a mandrel having an external upwardly and inwardly sloping frusto-conical expander surface, said mandrel having an upper section having a substantially cylindrical outer surface above and connecting with said expander surface; a plurality of slip shoes supported around said expander surface for longitudinal movement along said surface between a retracted and an expanded position, each of said slip shoes having an upper inner fragmentary cylindrical surface connecting with a lower inner fragmentary frusto-conical surface, said fragmentary cylindrical surface mating with said cylindrical surface on said mandrel above said expander surface when each of said slip shoes is in retracted position, said inner frusto-conical surface of each of said slip shoes mating with said expander surface when each of said slip shoes is in expanded position, each of said slip shoes having a lower end outwardly extending flange provided with a longitudinally and radially extending recess for receiving a slip lug; a slip operator positioned on each of said slip shoes for longitudinal movement relative to said mandrel and said slip shoe, each said slip operator having an upper internal cylindrical surface adapted to mate with said cylindrical surface on said mandrel above said expander surface, each said slip operator having a lower inner fragmentary frusto-conical surface adapted to mate with the outer frusto-conical surface of said slip shoe when said slip operator is in a fully expanded position, each said slip operator having an outer fragmentary frusto-conical surface, each said slip operator having an upper end outwardly extending flange, said flange having lug end sections each protruding beyond the adjacent edge of said slip operator; a slip positioned for longitudinal movement on the outer surface of each of said slip shoes and a supporting slip op-

erator positioned partially between said slip shoe and said slip, each said slip having an outer substantially cylindrical toothed surface and an inner fragmentary frusto-conical surface mating with the outer surface of the supporting slip operator when said slip operator and said slip are in fully expanded positions with said slip operator wedged downwardly between said slip shoe and said slip, each said slip having a lower end lug section received within said longitudinally and radially extending recess in said lower end flange on the supporting slip shoe, said lug section on said slip having an inwardly extending lip engaged over the lower end of said supporting slip shoe within said recess of said lower end flange of said shoe interlocking said shoe and said slip to limit relative longitudinal movement between said shoe and said slip; laterally operable slip retainer springs interconnected between corresponding sides of said slips extending laterally across said mandrel for holding said slips around said mandrel biasing said slips inwardly toward said expander surface and said cylindrical surface on said mandrel above said expander surface; a tubular fishing neck slidably engaged over said mandrel above said expander surface, said fishing neck having an internal downwardly opening annular recess around said cylindrical surface on said mandrel above said expander surface; each of said retainer springs having an upper end apex section extending into said annular recess of said fishing neck; a longitudinally operable spring positioned within said internal annular recess of said fishing neck, the upper end of said longitudinally operable spring being engaged with an upper end surface of said fishing neck defining the upper end of said internal annular recess of said fishing neck and the lower end of said longitudinally operable spring being engaged with the upper end apex sections of said retainer springs for biasing said springs downwardly; a tubular operator sleeve supported concentrically around said mandrel engaged along an upper end section with a lower end section of said fishing neck, said operator sleeve extending downwardly around said mandrel below the lower end of said expander surface on said mandrel, said operator sleeve having lateral windows each receiving and permitting lateral expansion of one slip shoe, slip operator, and slip unit to permit lateral expansion and contraction of said slips for releasably engaging a surface around said anchoring device; said operator sleeve having a surface defining the upper end of each of said lateral windows, said surface being engageable with the upper end of the operator sleeve positioned within said window for moving said operator sleeve longitudinally downwardly; said operator sleeve having surfaces defining lateral upper end side edges of each of said lateral windows forming lateral end recesses for receiving said laterally extending lugs on each of said operator members for holding each of said operator members within its lateral window against longitudinal movement relative to said operator sleeve; said operator sleeve having surfaces defining the lower end of each of said lateral windows for engaging the lower end of each of said lower end lugs on each of said slips for moving each of said slips longitudinally upwardly responsive to upward movement of said operator sleeve for reTRACTING said slips; and locking means interconnected between said operator sleeve and said mandrel below said expander surface for releasably holding said operator sleeve at a lower end position for holding said slips in radially expanded positions.

12. A well tool in accordance with claim 11, including an external annular radially expandable seal supported around said mandrel below said operator sleeve, said seal being expandable and lockable in an expanded position responsive to longitudinal movement of said operator sleeve.

13. An anchoring device for wells comprising: mandrel means; slip means supported on said mandrel means for releasably engaging a surface surrounding said anchoring device to hold said anchoring device against longitudinal movement in a first direction relative to said

surface; said slip means being adapted to be urged into tighter locking engagement with said surrounding surface responsive to a force on said mandrel in said first direction; retainer means for yieldably holding said slip means radially inwardly around said mandrel means; expander means on said mandrel and cooperating expander means carried by said slip retainer means engageable with said slip means to expand said slips to locking engagement with said surrounding surface; and yieldable compressible means adapted to bias said slip retainer means in a direction to expand said slips.

14. An anchoring device for wells comprising: mandrel means; said mandrel means having an expander surface sloping inwardly in a first direction toward said mandrel means; slip means supported on said expander surface for movement in said first longitudinal direction for retracting said slips and for movement in a second longitudinal direction for expanding said slips into releasable engagement with a surface surrounding said device; first spring means operatively engaged with said slip means for supporting said slip means on said expander surface and biasing said slip means inwardly toward said surface; second spring means operatively engaged with said first spring means for biasing said slip means along said expander surface in said second direction; slip operator means engaged between said slip means and said mandrel

means for movement in said second direction to expand said slip means and for movement in said first direction to release said slip means from locking relationship with said surrounding surface; and sleeve means longitudinally 5 slidably supported around said mandrel means for engagement with said operator means and said slip means for expanding and contracting said slip means, said slip means being urged into tighter relationship with said surrounding surface by an upward force on said mandrel means and being releasable from said surrounding surface by an upward force on said sleeve means.
